Inventor,

Orlando W. Hart

Attest, J. A. Highland,
William F. Patten

UNITED STATES PATENT OFFICE.

ORLANDO W. HART, OF FALL RIVER, MASSACHUSETTS.

POLICE-PATROL SYSTEM.

SPECIFICATION forming part of Letters Patent No. 606,865, dated July 5, 1898.

Application filed August 3, 1897. Serial No. 646,874. (No model.)

To all whom it may concern:

Be it known that I, ORLANDO W. HART, residing at Fall River, in the county of Bristol and State of Massachusetts, have invented 5 certain Improvements in Police-Patrol Systems, of which the following is a specification.

The present invention relates to telephonic and telegraphic signaling-circuits, and has especial reference to the circuits employed 10 for police purposes in towns and cities.

In the circuits for police systems it is usual to place the transmitting-telephone at all of the street-boxes in a local circuit, and it has been found that the local batteries in each 15 box, whether those employing a liquid electrolyte or a paste in what are known as "dry" batteries, freeze up in cold weather and are the cause of trouble and annoyance in many ways. My invention aims to avoid such difficulties, and to this end I arrange a police-circuit in which all the telephone-transmitters therein are energized from a common battery located at the central or police station. In the normal condition of the circuit—that 20 25 of disuse—the receiving-telephone in each box is hung upon a hook-switch, which, being thereby depressed, cuts out the telephone-transmitter, and the main circuit is continued in an alternate path through the signal 30 35 break-wheel to the next box. When the telephone-transmitter at any station on the circuit is in use and the receiver is off its hook, the latter in rising changes the circuit and makes a new path for the main circuit through the transmitter, which is thus in circuit with its own break-wheel and of the break-wheels in all the other police-boxes in the circuit and the apparatus at the central station.

My invention consists also in the telephone-transmitter employed at the several stations. It is of unusual construction and its principle of operation is the reverse of the instruments in use—that is to say, when the air-vibrations strike the diaphragm they cause a 40 45 separation of the electrodes instead of a compression of the same and when the instrument is most active presents the greatest resistance to the circuit, and consequently when a person is listening and not speaking, or when 50 55 the transmitter is the least active, it forms the least resistance in the circuit. I prefer

to connect an impedance or choking coil in parallel with the electrodes of the transmitter, and when conversation is going on the resistance of the circuit is increased and diminished in an undulatory manner by the expansion and compression of the electrodes and the to-and-fro currents of electricity occasioned by the air-vibrations meet with resistance in the impedance-coil and occasion reflex currents or "kicks," which increase the intensity of the charge upon the circuit. I prefer to connect the receiving-telephone in a local circuit which is in inductive relation with the main circuit, and as the primary coil 60 65 is in the main circuit but little resistance is added thereto.

When a policeman at a box is talking with an officer at the central station, a patrol emergency or other telegraphic signal may be 70 transmitted from any other box to the central station and be received there by the relay-printer or other receiving apparatus in the usual manner, as the effect of the presence of the telephone-transmitters in the main circuit increases the line resistance but very 75 slightly, not sufficiently to disturb the telegraphic signals, and as the signals are sent infrequently there is no inconvenience occasioned to telephonic transmission, as the telephonic receivers are in a local circuit, all of which I will now proceed to describe, and point out in the claims.

Figure 1 of the drawings is a diagrammatic representation of a police signal-circuit embodying my invention, and Figs. 2 and 3 are respectively sectional views of a telephone-transmitter, and of a detached enlarged view of its electrodes.

A is the police central office or headquarters, and B, C, and D are police patrol-boxes connected together by the wire L.

The wire L on the left side of the central station A includes the battery e, which is common to all the stations, and the relay f, 95 which operates the recorder for all the telegraphic signals and terminates at the hook-switch 17.

The wire L on the right side terminates at the point 10, from whence the wire 11 extends to a spring 16, which rests upon the end 100 of the hook-switch, and is thereby held away

from the spring 15, which is connected by wire 14 through the transmitter-electrodes and by wire 13 and primary p of induction-coil I^2 to point 10.

5 a^2 is an impedance or electromagnetic coil in parallel with the transmitter T .

t is the telephone-receiver upon the hook-switch and in a local circuit with the secondary s of the coil I^2 .

10 The apparatus of a police signal-box is partly shown at station C and is a reproduction of that described of station A, except that a call-bell b is shown in the wire 5 and that a break-wheel c and spring d therefor are shown 15 in circuit.

The apparatus for sending telegraphic signals by means of the break-wheel and the means for recording the same at the central office are not shown, but are well understood 20 by those familiar with the art.

The special form of telephone-transmitter is shown in Figs. 2 and 3, in which h is the case or box, and g the mouthpiece or opening into the box, across which on the inside is secured 25 by the screws m in the bar i , into the center of which is threaded the screw j , whose end presses upon a metal cap k upon the end of a round piece of carbon x , whose conical end fits into the conical depression in the carbon 30 piece y , whose opposite end fits into a conical depression in the third piece of carbon z , which fits in a metal cap carried on the inside of the diaphragm n . The diaphragm n is held in place at its edges by a ring-clamp 35 o , in which are screwed the binding-posts r and u , the former being connected by wire 19 to the metal bar i and the latter to the diaphragm n by the wire 18.

When the circuit is not in use, a current 40 flows from battery e over the circuit L , through the relay f , hook 17, spring 16, wire 11, circuit L , through each police-box, spring d , break-wheel c , wires 9 and 5, spring 3, hook 1, to the battery, and a telegraphic signal 45 can be sent in to operate the relay f , as usual.

When the telephone t is off the hook 1, say at station C, the circuit is, as just described, at boxes D and B through the break-wheels 50 and around the transmitter T ; but at station C it is through the break-wheel c , wire 9, primary p , wire 7, electrodes x y z , spring 25, hook 1, to wire L , and a similar circuit is established at station A when the telephone is 55 off its hook. Conversation can now take place over a comparatively-low-resistance circuit, and a telegraphic signal can be sent in from boxes B or D without interruption to the telephonic circuit and the relay f operated 60 without any difficulty. By the use of this form of low-resistance telephone-transmitter in the circuit with a battery of sufficient electromotive force to operate the telegraph-signals there is no tendency to the formation 65 of arcs between the electrodes, which are formed in a high-resistance transmitter of the ordinary type and are the cause of

humming noises in the circuit, which are so prevalent as to make conversation difficult and unsatisfactory.

70 Means are provided whereby the central station can call any substation, consisting of the double switch or key S , whose bars rest normally upon the contacts 40 and 60, and the main circuit continues through them. 75 The call-bell b at each patrol-box is of the ordinary polarized type, requiring alternating currents to operate it. The switch S is so constructed that when it is moved rapidly back and forth and causes its respective bars 80 to pass from contact 40 to 50 and from 60 to 70, and reversely, and thereby sends currents of opposite polarity from battery e over the circuit and operates the bells b , the circuit shall not be opened. The pairs of contacts 85 are placed so near to each other that as each bar passes away from one contact it makes connection with the second before leaving the first, and the switch may properly be termed a "circuit-continuity-preserving pole-changer." 90 It will be readily understood that should the circuit be opened between the said contacts the neutral relay f would be demagnetized and a false signal received. Each patrol-box has a definite prearranged signal in a manner 95 well understood.

Having fully described the invention, I claim—

1. A signaling system consisting of a closed circuit extending through a central station 100 and a plurality of substations or patrol-boxes; a battery common to all of the said stations; means for transmitting telegraphic signals from each substation or patrol-box to the central station, and means for receiving the same 105 at said station; and means at all of the stations for transmitting and receiving telephonic signals consisting of a low-resistance transmitter whose contacts are upon the front of the diaphragm and directly in the circuit 110 as set forth; and a magneto telephone-receiver in inductive relation with the circuit.

2. A signaling system consisting of a closed circuit extending through a central station and a plurality of substations; a battery common to all the said stations; means for transmitting telegraphic signals from each substation to the central station and means at the latter station for receiving the same; means at all the stations for transmitting and receiving telephone-signals, consisting of a microphone having a plurality of contacts in the main circuit supported between a fixed or rigid support near the mouthpiece and a diaphragm or vibrating surface at the rear of 125 said support; and a magneto telephone-receiver in inductive relation with said circuit.

3. A police or other signaling system adapted for telegraphic and telephonic signaling, consisting of a closed circuit including telegraphic transmitting apparatus at a plurality of substations or patrol-boxes and telegraphic receiving apparatus at a central station; a battery common to all of the said stations;

and means at all of the stations for transmitting and receiving telephonic signals consisting of a receiving-telephone in inductive relation with the main circuit; a telephone support or switch; a microphone having a plurality of contacts in series with each other, supported in an inclosing case between the front of a diaphragm or vibrating surface and a fixed or rigid support, in an alternate path of the main circuit, which path is open when the telephone is upon the switch, and which forms a part of the main circuit when the telephone is removed from the said switch.

4. A police or other signaling system adapted for simultaneous telegraphic and telephonic signaling, consisting of a closed circuit extending through telegraphic apparatus at a central station and also at a plurality of substations or patrol-boxes; a battery common to all of said stations; means for transmitting telegraphic signals from each substation or patrol-box to the central station, and means for receiving the same at said station; means at all of the stations for transmitting and receiving telephonic signals consisting of a receiving-telephone in inductive relation with the main circuit, a telephone support or switch, a low-resistance transmitter operating as set forth in an alternate path of the main circuit, which path is open when the telephone is upon the support or switch, and which forms a part of the main circuit when the telephone is removed from the said switch, and an electromagnetic or impedance coil in parallel with the electrodes of the transmitter, as set forth.

5. A telephone-transmitter consisting of a

case, a mouthpiece on the front of the case, a diaphragm at the rear of the case, a plurality of electrodes extending from the diaphragm toward the mouthpiece and provided thereat with a rigid support and with means of adjustment.

6. The combination in a police-patrol system, with a closed circuit including a battery, of a plurality of substations or patrol-boxes and a central station; telegraphic signal-transmitting apparatus at each substation, and telegraphic signal-receiving apparatus at the central station; telephonic transmitting and receiving instruments at all of the stations normally disconnected from the circuit, the transmitting instruments having a plurality of contacts in series, supported in an inclosing case between the front of the diaphragm and a fixed or rigid support; the receiving instruments being in inductive relation to the main circuit and normally suspended from a support or switch; whereby when the receiving-telephones are suspended from the switches telegraphic signals only can be transmitted over the circuit, and when the telephones at any two stations are removed from their switches both telegraphic and telephonic signals can be transmitted.

In testimony whereof I have signed my name to this specification, in the presence of two subscribing witnesses, this 19th day of February, 1897.
